PAIR OF SUNGLASSES OR SIMILAR ARTICLE

Joseph Auchter, Lincoln Park, Pa., assignor to Willson Products, Inc., Reading, Pa., a corporation of Pennsylvania

Application May 12, 1949, Serial No. 2,598

Term of patent 14 years

(Cl. D57—1)

To all whom it may concern:

Be it known that I, Joseph Auchter, a citizen of the United States, residing at Lincoln Park,
in the county of Berks and State of Pennsylvania, have invented a new, original, and ornamental Design for a Pair of Sunglasses or Similar Article, of which the following is a specification; reference being had to the accompanying drawing, forming part thereof, wherein:

Fig. 1 is a top plan view of a pair of sunglasses
embodying my new design;

Fig. 2 is a front view, and

Fig. 3 is a side view thereof.

I claim:

The ornamental design for a pair of sunglasses
or similar articles, substantially as shown.

JOSEPH AUCHTER.
